(57) **CLAIM**

We claim the ornamental design for a screen furniture unit, as shown and described.

DESCRIPTION

FIG. 1 is a front perspective view of a screen furniture unit embodying the present invention;

FIG. 2 is a front view of FIG. 1, taken in a direction perpendicular to a center front surface of the screen;

FIG. 3 is a top view of FIG. 1;

FIG. 4 is a rear view of FIG. 2; and,

FIG. 5 is a side view of FIG. 1.

The dashed lines in FIGS. 1–5 show the environment and do not form a part of the design sought to be patented.
